Primary Examiner — Garth Rademaker*Assistant Examiner* — Lilyana Bekic(74) *Attorney, Agent, or Firm* — Dorsey & Whitney LLP(57) **CLAIM**

We claim the ornamental design for a base for an oral irrigator, as shown and described.

DESCRIPTION

FIG. 1 is a front isometric view of a base for an oral irrigator showing our new design.

FIG. 2 is a rear isometric view of the base for an oral irrigator of FIG. 1.

FIG. 3 is a front elevation view of the base for an oral irrigator of FIG. 1.

FIG. 4 is a rear elevation view of the base for an oral irrigator of FIG. 1.

FIG. 5 is a left side elevation view of the base for an oral irrigator of FIG. 1.

FIG. 6 is a right side elevation view of the base for an oral irrigator of FIG. 1.

FIG. 7 is a top plan view of the base for an oral irrigator of FIG. 1; and,

FIG. 8 is a bottom plan view of the base for an oral irrigator of FIG. 1.

The broken lines in the drawings illustrate portions of the base for an oral irrigator and the bounds of the claim, and form no part of the claimed design.
